United States Patent Office

Des. 179,688
Patented Feb. 12, 1957

179,688

SET OF TOY BUILDING BLOCKS OR SIMILAR ARTICLE

Nathan Kaplan, Flushing, N. Y., assignor to The Plas-Trix Company, Inc., Brooklyn, N. Y., a corporation of New York

Application April 20, 1956, Serial No. 41,139

Term of patent 14 years

(Cl. D34—15)

FIG. 1.

FIG. 1a.

FIG. 2.

FIG. 2a.

FIG. 3.

FIG. 3a.

FIG. 4.

FIG. 4a.

Figs. 1 and 1a are perspective views of the blocks in a set of toy building blocks or similar article, showing my new design;

Figs. 2 and 2a are top plan views thereof;

Figs. 3 and 3a are bottom plan views thereof; and

Figs. 4 and 4a are end elevational views thereof.

I claim:

The ornamental design for a set of toy building blocks or similar article, as shown.
